UNITED STATES PATENT OFFICE

LAWRENCE D. STRONG, OF MAYWOOD, ILLINOIS

CHANGE OVER

Application filed December 8, 1927. Serial No. 238,559.

This invention relates to change-overs or devices for cutting off the light from projecting machines, such as moving picture machines, stereopticons and effect machines. 5 While my improved change-over device may be used with various types of projecting machines, it is particularly adapted for use in connection with projecting machines having low intensity lamps with wider beams of 10 light distribution and larger lenses. On account of the larger sized light beams, it is more difficult to properly cut off the beam without undue distortion or objectionable effects on the screen. The present invention 15 is designed to properly handle such beams and not only provides means for cutting them off instantaneously in a satisfactory manner but also provides means whereby it may be operated by hand to give a slow iris 20 fade out when desired.

Among the objects of this invention are to provide an improved change-over device of the character indicated; to provide a change-over device having a plurality of coating 25 radially swinging shutters with electrically operated means for opening and closing the same; to provide a combined electric and hand operated change-over device of this character; to provide a change-over with 30 electric operating means and means whereby the current will be automatically cut off from the operating means immediately after operation; to provide a change-over having a plurality of shutter blades with solenoids for 35 operating the same and having a switch arranged to cut off the electricity immediately after each operation so that it is impossible to burn out the coils; to provide an improved switch for devices of this character; and to 40 provide such other advantages and novel features as will be described more fully hereinafter.

In the accompanying drawings illustrating this invention,

45 Figure 1 is a front view with the cover removed;

Figure 2 is a sectional view taken on the line 2-2 of Figure 1;

50 Figure 3 is a sectional view taken on the line 3-3 of Figure 1; and

Figure 4 is a diagrammatic view showing the circuits.

In the particular form of the device as shown in these drawings, the operating mechanism is enclosed in a box or casing 6 which is provided with a cover 7 and which may be supported in a port opening in the front wall of the booth in any suitable manner or in some instances, if desired, may be mounted directly in front of the projecting machine. 55 The front wall 8 has an opening 9 which is provided with an inwardly projecting flange 10 and the cover has a hole 11 which registers with the hole 9 or is in alignment therewith and has an inwardly projecting flange 60 12. In one commercial form as now constructed, these openings are five inches in diameter which is sufficiently large to pass all light rays from the projectors, stereopticons and effect machines now in common use. 65

The shutters 13, 14 and 15 are preferably of the iris type and are pivoted on studs 16, 17 and 18, which engage with lugs around the flange 10. The blades are held in spaced relation so that they will clear each other by means of sleeves 19, 20 and 21 which fit over the studs and are of different heights, as shown in Figure 2. These sleeves are reduced adjacent to the flange 10 to form bearings for the shutter operating ring 22 which 70 is rotatably mounted thereon. This ring has pins 23 for engagement with slots 24 in the shutters for swinging the same, the arrangement being such that as the ring is moved in an anti-clockwise direction, as shown in Figure 1, the shutters will be swung in to close the opening, and then as the ring is moved in the opposite direction, the shutters will be 75 swung out to open position, as shown in this figure. 80

The ring 22 has a handle 25 which extends outwardly through a slot 26 in the side of the casing whereby the device may be manually operated. The ring 22 is preferably provided with an overthrow spring which tends to 85 throw it to complete open or complete closed position. In the arrangement shown, the spring 27 is attached at one end to a pin 28 on the frame and at the other end to the free end of an arm 28' which is pivoted at 29 to 90 100

the frame or casing. The outer or free end of the arm 28 is provided with a slot 30 for receiving a pin 31 on the arm or handle 25. As shown in Figure 1, the spring is past dead center and tends to hold the shutters in open position. When the ring is swung in the opposite direction to close the shutters, the spring will pass the dead center and tend to hold the parts in closed position.

10 The change-over is electrically operated by solenoids 32 and 33 which are rigidly secured in the bottom of the box or casing 6. The plunger 34 of the solenoid 32 is connected by a link 35 with a projection 36 on the ring 22. The plunger 37 of the solenoid 33 is connected by a link 38 with the arm 25. When current is supplied to the solenoid 33 its plunger will be drawn in, thereby swinging the device to open position, as shown in 15 Figure 1, and when current is supplied to the solenoid 32, its plunger will be drawn in, thereby swinging the parts to closed position.

16 As these solenoids require a comparatively heavy current to operate them satisfactorily, I have provided a novel device for automatically cutting off the current from the respective solenoids after they have been actuated so that it is impossible for the operator 20 to burn out the solenoids by permitting current to flow therethrough for too long a period. While the circuit is thus broken to the operating solenoid, it is also closed to the other solenoid so that it will be in condition 25 for operation. This is accomplished by means of a double switch which is actuated by the shutter opening and closing mechanism. In the particular arrangement shown, the ring 22 is provided with an arm 39 formed 30 of insulating material and carrying a contact pin 40 which is adapted to engage at times with two sets of switch blades 41, 42 and 43, 44. The bent ends of the blades 41 and 42 engage with sockets or recesses 45 and 46 in contact brackets 47 and 48 which are carried on a block of insulating material 49 mounted in a chamber 50 at the top of the box 6. The blades are resiliently held in engaging position by means of bolts 51 and 52 and springs 53 and 54, as will be readily understood from Figure 1. The switch blades 43 and 44 are similarly connected with contact brackets 55 and 56 also secured to the block 49. The forward ends of the blades 5 are bent outwardly to facilitate the engagement of the contact 40 therewith and by bending these out more or less the length of time that current is supplied to the respective solenoids may be regulated in order to increase or decrease the power, and consequently the speed of operation. The circuit for the solenoid is from a contact or binding post 57 to a common wire 58 to switch blade 41 and 43, contact or binding post 59 through 9 wire 60, solenoid 32, wire 61 to switch blade

44. From terminal or contact 62 through wire 63, solenoid 33, wire 64 to switch blade 42. The contacts or terminals 57, 59 and 62 are connected with the line wires 65, 66 and 67 from any suitable source of supply, and the circuits to the respective solenoids may be opened and closed by a switch 68. When the switch 68 is closed to supply current to the wires 65 and 66, the solenoid 32 will be actuated, the current passing from terminal 59 through wire 60, solenoid 32, wire 61, switch blade 44, switch contact 40, switch blade 43, wire 58, terminal 57, wire 65. This will actuate the solenoid 32 to close the shutters, and as the ring 22 is rotated, the arm 39 will carry the contact 40 away from the blades 43 and 44, thereby opening the circuit to the solenoid 32 and stopping the supply of current thereto. This will usually occur at about the time the spring 27 passes the dead center and the spring together with the inertia of the parts will insure the closing of the shutter. As the arm 39 continues its movement, the contact 40 will be brought into engagement with the blades 41 and 42, thereby closing the circuit to the solenoid 33 so that it will be in condition to operate to open the shutters when the switch 68 is operated to supply current to the wires 65 and 67, the circuit for this operation being wire 65, terminal 57, wire 58, switch blade 41, contact 40, switch blade 42, wire 64, solenoid 33, wire 63, terminal 62 and wire 67.

Usually a number of these change-overs are used in a single operating booth and the switches, such as indicated by the switch 68 are foot operated, but on account of the automatic circuit breaking mechanism just described, no damage will result even if the switch 68 is kept closed for an indefinite period.

100 My improved change-over may, of course, be made in various sizes or styles for different conditions and changes may be made in the details of construction without departing from the scope of this invention; therefore I do not wish to be limited to the exact arrangement herein shown and described except as set forth in the following claims, in which I claim:

115 1. A change-over comprising a frame having an opening therethrough, shutter blades for opening and closing said opening, an electro-responsive device for opening the shutters, an electro-responsive device for closing the shutters, and means for automatically opening the circuits to the respective devices when they have been actuated.

120 2. In a change-over, the combination of a plurality of shutters, means for actuating the shutters to open and close the same, a solenoid connected with the actuating means for moving it to open the shutters, a second solenoid connected with the actuating means for moving it to close the shutters, electric cir- 125

130

cuits for said solenoids, and switches actuated by the opening and closing means for opening the circuits to the respective solenoids.

3. A change-over comprising a casing having an opening therethrough, a plurality of shutters pivoted adjacent to the opening, a ring, pins on said ring engaging with slots in the shutters for swinging the shutters, a handle projecting from said ring, a closing solenoid connected with the ring, an opening solenoid connected with the ring, pairs of switch blades arranged adjacent to the ring, an arm projecting from the ring and bearing a contact adapted to engage at times with the respective pairs of blades, and electric circuits for the respective solenoids, each circuit including one of said pairs of switch blades, the arrangement being such that the blades of the respective pairs will be connected or disconnected at times by the contact carried by said arm.

4. A change-over comprising a casing having an opening therethrough, a plurality of shutters pivoted adjacent to the opening and adapted to open and close the same, a ring rotatably mounted adjacent to the shutters, means connecting the ring with the shutters and adapted to swing the shutters as the ring is rotated, a handle projecting from the ring through the casing, overthrow spring mechanism operatively connected with the casing and handle and tending to throw the ring to open or closed position respectively, a solenoid for moving the ring to open position, a link connecting the solenoid plunger with the ring, a second solenoid for moving the ring to closed position, a link connecting the plunger of this solenoid with the ring, an electric circuit for the first named solenoid including a pair of switch blades, an electric circuit for the second named solenoid also including a pair of switch blades, and a contact member carried by said ring and adapted to engage with the respective pairs of switch blades to open and close the circuits to the solenoids, substantially as described.

5. An electric change-over device of the character set forth having multiple blade iris type shutters, solenoids operatively connected with said shutters for actuating the same, means whereby the current is automatically cut off from the respective solenoids immediately after operation, and means tending to hold the shutters in open and closed positions, respectively.

LAWRENCE D. STRONG.
